FIG. 1.

FIG. 2.

FIG. 3.

FIG. 4.

Inventor -
Herbert Henry Berry
By
B. Singer, Atty.

UNITED STATES PATENT OFFICE.

HERBERT HENRY BERRY, OF LONDON, ENGLAND.

ELECTRIC FIRE.

1,354,594.

Specification of Letters Patent.

Patented Oct. 5, 1920.

Application filed October 3, 1919. Serial No. 328,147.

To all whom it may concern:

Be it known that I, HERBERT HENRY BERRY, a citizen of the United Kingdom of Great Britain and Ireland, and resident of 5 the Switch House, 86 Newman street, London, W. 1, England, have invented certain new and useful Improvements Relating to Electric Fires, of which the following is a specification, such as will enable others 10 skilled in the art to which it appertains to make and use the same.

This invention relates to electric fires of the kind in which imitation fuel is arranged over electric lamps and in which rotary 15 flicker-producing devices are employed to produce fire-like effects.

According to the invention I arrange a resistance in a suitable case below the fire to produce both the requisite heat and a 20 glow effect, said case being movable so that it can be employed to support a kettle or other vessel for heating purposes.

The imitation fuel is preferably arranged over a wire-work frame inside which are the 25 electric lamps, the cover or top of the frame being movable to give access to the lamps said top having on its underside fans or propellers to produce the flicker. The fans are held by any suitable means and have pref- 30 erably a central pivot of the pin and inverted cup type.

The accompanying drawings illustrate by way of example how my invention can be carried out.

35 Figure 1 shows a dog grate α to which my invention is applied.

Fig. 2 is a side view of the grate shown in Fig. 1.

40 Fig. 3 shows a similar stove with a modification of the invention.

Fig. 4 shows a wire frame or basket supporting "fuel" and having a hinged cover on the underside of which the fans are mounted. This frame and "fuel" can be fitted 45 into any suitable fire place or stove and additional "fuel" added, or all the "fuel" may be loose.

Fig. 5 shows a fan and its bracket.

50 The basket or wire frame b contains the lamps $c c$ and has "fuel" d secured to it. Other "fuel" loose or attached may be used. The cover f of the frame supports the fans e by means of brackets g and, as can be seen in Fig. 5, these fans have hollow centers

and are mounted on fixed pins h , a small stop being provided at i to prevent the fans leaving the pins.

In Figs. 1 and 2 a case l containing any suitable electric heating element or resistance is pivotally mounted on the grate α 60 and can hang about vertically as shown by full lines or may be brought to a horizontal position (as shown by line and dot in Fig. 2) and supported by chains m .

Instead of pivoting the case l it may be 65 simply stood on edge or turned from that position so as to stand upright as shown in Fig. 3.

The resistances in the case l and the lamps $c c$ are preferably on different branches of 70 an electric circuit so that either may be used without the other and when used together the lamps and the imitation fuel with the flicker devices produce a very realistic fire and the resistance in the case produces the 75 heat necessary for effective warming purposes in addition to which the case l may have a silica or other such translucent front so that the glow of the resistance appears to be from the fire and when required, as above 80 stated, a vessel or other article to be heated may be placed on the case.

The pattern or style of the fire place may vary as required and obviously the shape of the parts forming the invention may be altered 85 as desired without departing from the spirit of the invention. Gas lights could be used instead of the lamps $c c$.

What I claim and desire to secure by Letters Patent is:—

An electric fire producing apparatus, in combination with fuel-simulating supporting means comprising an openwork metal guard, a movable top to said guard, an electric lamp in said guard, a fan supported by 95 the said top and positioned over the lamp, and a heating means including a resistance, said heating means being arranged for movement into a position to cause the glow of its resistance to simulate a fire reflection 100 and also arranged for movement into a position to support a cooking vessel.

In witness whereof I have hereunto set my hand in the presence of two witnesses.

HERBERT HENRY BERRY.

Witnesses:

HENRY FAIRBROTHER,
JAMES THOMSON.
